UNITED STATES PATENT OFFICE.

ROBERT F. McCRAKAN, OF RICHMOND, VIRGINIA.

SIPHON.

Application filed July 7, 1924. Serial No. 724,650.

To all whom it may concern:

Be it known that I, ROBERT F. McCRAKAN, a citizen of the United States, residing at Richmond, in the county of Henrico and

5 State of Virginia, have invented certain new and useful Improvements in Siphons, of which the following is a specification.

This invention relates to an improved siphon which is especially but not necessarily, adapted for use more particularly in chemical laboratories.

In carrying out this invention I have evolved and produced a type of siphon which is self-starting, flow controlling, non-dripping, and in which the tube or conduit is continuously open.

In chemical laboratories, and places where siphons are commonly used, it is the practice, so far as I know, to use pinch cocks, and other ineffective means for stopping the flow of fluid through the tube. In both instances, these pinch stop cocks are rather weak after a little use, and they permit leakage and, of course, wear out the rubber tubes prematurely.

It is, therefore, my purpose, as before stated, to provide a siphon which will obviate the necessity of employing valves, this result being accomplished by employing a conduit including a flexible portion which is of a length to permit the discharge end thereof to be readily disposed above and below the liquid level in the container, so that the flow of fluid may be readily started or cut off according to the elevation of the discharge end of this flexible portion.

It is also a feature of the invention, in providing a structure which is highly adaptable for connecting the discharge end 40 of the conduit with the neck of a bottle, so that the conduit may be suspended in an out-of-the-way position ready for immediate use.

Numerous other features and advantages 45 of the invention will become apparent from the following description and drawings:

In the accompanying drawing, forming a part of this application and in which like numerals are employed to designate like parts throughout the same:

Figure 1 is an elevation, with parts broken away and shown in section, of the improved siphon in association with a liquid containing bottle.

55 Figure 2 is a view showing a slightly different embodiment of the invention.

Referring now to the drawing, it will be seen that the letter B represents a bottle of the type frequently seen in laboratories and the like, the same being adapted to contain 60 distilled water, chemical fluids and the like, to be siphoned therefrom into another container. The neck of the bottle is closed by a suitable plug, in the form of a cork stopper S. The stopper is provided with a 65 vertical bore, through which the depending part P of a rigid tube T extends. This tube is of the usual design. Connected to the discharge end thereof is a section of rubber tubing R, which, we will assume, extends under ordinary circumstances, to about the point A. The tubing R and the tube T form the common and well known siphon and these constitute no part of the present invention.

75 The invention comprises an extra length of rubber tubing 1, extending from the point A to any desired point. This extra tubing 1, of necessity, must be flexible, and, as stated, it is preferably of rubber. A 80 short rigid tube 2 of any appropriate design, is connected to the free end of the tubing 1, and although it is not essential in all instances, this tube is equipped, at its free extremity, with a cork member 3. The 85 stopper 3 is adapted to be snugly received in the cup 4 on the upper end of the tube 5 extending through an opening in the aforesaid stopper S.

90 Before considering the method of use of the device, I wish to direct attention to Figure 2, wherein a slightly different embodiment of the invention is shown. It will be observed that in Figure 1, a comparatively small cork stopper is used, and in this form 95 it is essential to provide the cup 4 for the reception of the stopper 3 on the tube 2. This is not essential in all instances, however, for, where a large stopper D is used, the stopper itself may be formed with a 100 tapered opening C for reception of the stopper 3^a carried by the tube 2^a. Otherwise, this view shows nothing different from that already considered.

105 It has been before stated, that the primary feature of the invention is based upon the fact that the improved siphon is self-started. Obviously, this is a decided advantage, in that it obviates the necessity of sucking upon the tube, or in other ways 110 creating suction to start the flow of the fluid. Assuming that the bottle B is filled

with water to the level indicated, and that the siphon conduit is filled with water up to the level of the bottle, it will be seen that by lowering the discharge end of the tube 2, below the liquid level in the bottle, the liquid will begin to discharge through the conduit immediately, thus enabling any supplemental receptacle to be filled with the water from the main 10 receptacle or bottle. As soon as this discharge end is raised above the liquid level, the flow will stop. So long as the free end of the conduit is suspended into position above the liquid level, the use of valves 15 and pinch stopcocks is unnecessary. From the illustration it will be obvious that the means shown for suspending the tube is quite novel, in that the stopper 3 can be seated in the cup 4 and the tube suspended 20 in a position for convenient use. At this time, dust and extraneous particles are prevented from entering and contaminating the fluid in the bottle.

Before closing, I would state that in practice the conduit may be considerably long 25 so that the discharge end thereof may be carried to a point considerably below the liquid level in the bottle. This is essential to start the initial flow of fluid into the 30 siphon conduit. For instance, when it has been transferred from one bottle to another and it is desired to produce the self starting action. Of course, if the self starting 35 feature is not desirable, the tube may be shorter in length and the old method of starting may be utilized.

It is thought that the foregoing description in connection with the drawings will suffice to enable a clear understanding of 40 the invention to be had. For this reason, I do not believe that it is necessary to go more into detail.

While I have shown and described the

preferred embodiments of the invention, it is to be understood that minor changes coming within the scope of the adjoined claims may be resorted to, if desired. 45

I claim:

1. A device of the class described comprising a liquid containing bottle, a liquid elevating tube, a stopper fitted into the neck of the bottle, said tube having a portion extending downwardly through an opening formed in said stopper and into the interior of the bottle, the upper end of said tube disposed above said stopper, a relatively long section of flexible tubing connected to said elevating tube and adapted to extend down one side of the bottle, and to be looped beneath the bottom of the bottle and 50 extended upwardly along the opposite side, a stopper carried by the free end of said tubing, a second tube extending through the stopper in the neck of the bottle, the last named tube being provided on its upper end 55 with a cup, the stopper on the free end of the tubing being receivable in said cup. 60

2. A device of the class described comprising a liquid containing bottle, a liquid elevating tube, a stopper fitted into the neck 70 of the bottle, said tube having a portion extending downwardly through an opening in said stopper and into the interior of the bottle, the upper end of the tube being disposed above said stopper, a relatively long 75 section of flexible tubing connected to said elevating tube and adapted to extend down one side of the bottle, and to be looped beneath the bottom of the bottle and extended upwardly along the opposite side, a plug 80 carried by the free end of said flexible tubing, the aforesaid stopper being equipped with a socket shaped to snugly receive said plug. 85

In testimony whereof I affix my signature.

ROBERT F. McCACKAN.
